UNITED STATES PATENT OFFICE.

RICHARD E. ROSEWARNE, OF COVINGTON, KENTUCKY, ASSIGNOR TO HOMER J. YOUNG
AND RICHARD E. ROSEWARNE, TRUSTEES.

CUTTER-HEAD FOR CIGARETTE-MACHINES.

1,242,478.

Specification of Letters Patent. Patented Oct. 9, 1917.

Application filed August 9, 1915. Serial No. 44,366.

To all whom it may concern:

Be it known that I, RICHARD E. ROSEWARNE, a citizen of the United States, and residing at Covington, in the county of Kenton and State of Kentucky, have invented a new and useful Improvement in Cutter-Heads for Cigarette-Machines, of which the following specification is a full disclosure.

This invention relates to severing devices for severing a continuously moving work into determined or measured lengths, having utility in cutting rope-like cigarette stock inclosed in a paper casing into cigarettes, to which the invention is primarily directed.

The cutter has a rotary motion and during its rotation is carried in an orbital or circuitous path around a work guiding member to intervally intersect the work guiding spout for severing the work into determined or measured lengths. The cutter therefore has a planetary motion, rotatively about its own axis and about the axis of its rotating support, as well as a lateral or longitudinal movement in motions of reciprocation and in one direction at a rate coincident with the feed of the work. The guiding spout moves unitarily with the cutter in its reciprocating motion, but non-rotatively confined. This provides for a continuity of motion of the moving parts and work.

An object of my invention is to provide a severing device wherein the general organization adapts itself to the use of a plural number of cutters moving as a unit in an orbital path to successively intersect a work feed spout in either the singular or plural number, with the cutting edge of the cutters continuously guided in a circular path and when bisecting the spout.

Another object of the invention consists in providing a stationary journal or axle member as an axis about and upon which planetary cutters are rotatively and transversely movable, in either the singular or plural number and as a support for a feed spout member in either the singular or plural number, adapted to be intersected by

the rotating cutters, and moving as a unit therewith transversely or longitudinally with a common axis.

Further, in the provision of a cam or pitch member rotatable about said axle for moving the parts transversely on motions of reciprocation coördinately with the feed of the work or cigarette stock during a severing interval.

Various other features and advantages of the invention will be more completely disclosed in the description of the accompanying drawings, said drawings forming a part of this specification, containing letters of reference with like characters denoting corresponding parts throughout the several views, of which:—

Figure 1 is a top plan view of the severing device illustrating two cutters as a unit revolving in a common orbital path eccentrically about a feed table which the knife successively intercepts for severing the material moving through the feed tube. Fig. 2 is an end elevation thereof with the carrier devices for feeding the stock to the feed tube omitted. Fig. 3 is a partial section taken on line 3—3 Fig. 2. Fig. 4 is an elevation of a modified form of stock guiding or feeding member illustrating a plural number of feed tubes. Fig. 5 is a view similar to Fig. 2, illustrating the cutter devices in the singular number, and Fig. 6 is a partial sectional view on line 6—6 Fig. 5.

Referring to Figs. 1, 2, and 3 of the drawings, which illustrate the preferred embodiment of the invention in the employment of a plural number of cutters, 1 indicates a main frame structure supporting the severing devices and comprising a component of a cigarette machine. The cigarette stock in the nature of a rope-like strand is fed from the forming devices not shown upon a belt or tape 2 having one of the loops engaged over the pulley 3 properly located so that the cigarette stock is fed in alignment with the feed tube of the cutter or severing devices.

A bracket 4 is secured upon the main frame 1 having an arm 5 projecting for-

wardly for supporting a bearing member or axle 6. The bearing member 6 engages into a bore formed into the hub end of said bracket arm 5, and is rigidly secured to the 5 arm by the screws 7. Adjacent one end of the bearing member 6 I provide an annular non-rotative axially movable spout member 8 having a stud 9 axially projecting from one side and extended into a bore 10 formed 10 in the end of the bearing member and concentric therewith. The spout member 8 has a tubular spout 11 projecting eccentrically from its opposite side with the spout bore extended through said member 8 and continuing 15 with a tube 12 secured to and projecting from said member 8 and guidingly extended into a bore 13 longitudinally through the bearing member or axle 6. The stud 9 and tube 12 serving as means for non- 20 rotatively mounting the spout member upon the bearing member, but free to slide thereon axially. The mouth of the spout and axis of the guiding bore through the bearing member is located in alinement with the 25 moving cigarette stock fed from the carrier tape 3.

A cam wheel 14 which also serves as rotative support for the circular cutters or knife 15 is concentrically journaled upon the 30 periphery of the bearing member and capable of sliding axially thereon. The hub 16 at one end is provided with a coupling collar 17 fitting into an annular groove formed in the periphery of spout member 8 for connecting said member with the cam wheel to 35 axially reciprocate the same and move the guide spout with the moving cigarette stock at a corresponding rate of motion during a severing period, necessary for making a 40 straight cut across the moving stock. A gear 18 is secured upon the opposite end of the hub of the cam wheel in mesh with a gear 19 suitably journaled and supported and preferably provided with an enlarged 45 or elongated face to maintain a constant full width mesh with the gear 18 in its sliding motion. The gear 19 is driven from a suitable source and at a proper speed commensurate for cutting the continuous cigarette stock into determined lengths. 50

The construction of the parts above described for the purpose herein is applicable to any of the styles for severing device shown in the various modifications, for 55 either a single or plural number of cutters operating across a single feed spout or tube and from a general aspect, for the double or series of feed spouts. In the latter instance provision need only be made in the 60 bearing member for the requisite number of passages through the spout and bearing members. In all instances due regard should be had for such mechanical variation required as to the design of cam out-

line or operating speed ratios necessary for 65 producing a desired length of cigarette which is represented by a non-cutting period or interval of the cutter or cutters.

The means for supporting the cutters is substantially the same for the singular or 70 plural number, and when the cutters are employed as shown it is preferable to mount the same diametrically opposite each other upon the cam wheel and therefore a detail description of one will be sufficient for the 75 purposes herein. The web of the cam wheel is provided with a laterally extended ear 20 having one side surface in plane with a wall of the opening 20^a formed in the cam wheel web, to receive and support the bearing block 21, which is secured, adjustable radially, by the screws 22, 22, respectively 80 passing through oblong slots in the ear 20. The bearing block 21 supports a shaft 23 axially coplanar with the axis of the cam wheel and longitudinally confined by the shoulder of an annular boss 24 integral with the shaft, at one end of the bearing, and by a collar 25 at the opposite end of the bearing. The end of the shaft 23 projecting 85 beyond the annular boss 24 provides a screw-threaded stud 26 for supporting the circular cutter 15 which is securely clamped to the shaft 23 by a nut 27. The cutting edge of the cutter extends into an annular 90 concentric groove 28 of the spout member 8, so that it will intercept the spout bore in its orbit. As illustrated the plane face of the cutter at its cutting edge engages with the adjacent groove wall serving to guide the 100 knife, avoiding any vibratory motion of the knife, and provides a shear action across the spout bore in addition to the rotary cutting action of the cutter. It is desirable to rotate the cutter upon its own axis independent of its orbital motion whereby the cutter has a planetary motion. The cutter and its shaft are independently rotated by a belt 29 which engages around and into the 105 annular groove 31 formed around the periphery of the shaft boss 24 and in a single cutter severing device the belt loops around and engages into an annular pulley groove 110 32 formed upon the periphery of the non-rotating spout member 8.

In the double cutter form of severing device the belt runs engage with the pulley groove of the spout member and upon opposite sides thereof, with the belt loops respectively connecting with the belt grooves of the cutter shafts as shown in Fig. 2. The orbital motion at the belt loops imparts a driving motion to the belt by reason of its frictional engagement with the non-rotative spout member, with the diameter of the belt surface of the knife determining the 125 rate of rotation of the cutter upon its own axis, which is preferably a high speed rate.

With a single cutter and single feed tube or spout intercepted by the cutter, only one severance is made to each revolution of the cam wheel. The severing performance however can be increased by either multiplying the number of feed tubes within the orbital path of the cutters or by multiplying the number of cutters operating across a single feed tube or spout, or either a combination in the plural of both cutters and feed tubes. Thus it will be apparent that in a unitary compact structure the capacity can be materially increased over the type of cutter heretofore employed for cutting cigarette stock into definite lengths.

In Fig. 4 a double spout or feed tube member is illustrated, with their feed bores arranged relatively diametrically upon opposite sides of the common axis, and of duplicate construction and as heretofore described in the singular, noting however, that the bearing member 6 must be provided with longitudinal guiding bores 13 in number equal to the number of feed tubes employed to guide the severed lengths to a point of delivery.

It will be observed that the feed or guide spouts are located between the axis about which the cutter revolves and the axis of the cutter, enabling the cutter edges to be continuously in mesh and guided within the groove 28. This enables the cutter edge to be adjusted to approximately contact with the bore edge of the spout imparting a shear action upon the material to be severed, producing a sharper cut of the paper casing inclosing the cigarette stock.

To translate the guide spout and cutter longitudinally with the feed of the work, the cam rim 33 of the cam wheel 14 is provided with opposite cam surfaces 34, 34, intervening and respectively engaging the non-translating or relatively stationary guide rollers 35, 35, (see Fig. 1) suitably journaled upon the bracket 4. The cam surfaces as a unit are of such outline or pitch as to move the cutters longitudinally with the work when they intersect the guide spout and in a retracting or opposite direction during a non-severing interval, and the non-severing interval coordinates to the feed rate of the work for determinate lengths into which the work is to be severed. It will be understood that by forming the cam faces at various angles the transverse or reciprocating movements of the cutter and feed spouts will be regulated to cut the work into any desired lengths, and that various constructions and outlines could be used with the apparatus herein to meet the various demands commensurate with their rotative speed, and number of cutters. It will also be understood that various forms of transmission means may be employed for the cut-

ters, but the use of a belt is preferred when possible, by reason of its smooth running and noiseless qualifications.

Having described my invention, I claim:—

1. In a severing device, a non-movable axle member, a planet cutter journaled and axially movable upon said axle, a guiding spout extending through said axle having a portion at point of cutter intersection moving axially with said cutter, and means for axially moving said parts in motions of reciprocation.

2. In a severing device, a stationary axle member, a cam wheel journaled and axially movable upon said axle member, a cutter journaled upon said cam wheel axially coplanar with the axis of said axle member, a non-rotatable guide spout axially slidable upon said axle adapted to be intersected by the cutting edge of said cutter and coupled to said cam wheel to move axially therewith, and means for rotating said cam wheel.

3. In a severing device, a stationary axle member, a cam wheel journaled and axially movable upon said axle member, a cutter journaled upon said cam wheel axially coplanar with the axis of said axle member, a non-rotatable guide spout axially slidable upon said axle adapted to be intersected by the cutting edge of said cutter and coupled to said cam wheel to move axially therewith, means for rotating said cam wheel, and transmission devices connecting with said knife and axle for rotating said cutter about its own axis, and means for rotating said planet cutter about the axis of said axle member.

4. In a severing device, a stationary axle having a conduit longitudinally therethrough, a pitch member concentrically and slidably journaled upon said axle adapted to coöperate with stationary means whereby said pitch member through its rotation is moved laterally upon said axle in motion of reciprocation, a rotative cutter eccentrically journaled upon said pitch member, and a spout member supported upon said axle having a conduit joining with said axle conduit and adapted to be intersected by said cutter, said spout member connecting with said pitch member to be reciprocated thereby.

5. In a severing device, a support, a planet cutter revolvably journaled upon said support and adapted to sever the work at an intersecting location between the axis of the cutter and the axis about which it revolves, and non-rotatable means for guiding the cutter's edge continuously in its orbital path.

6. In a severing device, an axle member, a planet cutter mounted upon said axle, a work guiding spout intervening said cutter

and axle axis about which said cutter revolves to intersect said spout in each orbital revolution of said cutter; and means for translating said cutter and guiding spout 5 in motions of reciprocation longitudinally of the feed and at a rate corresponding with that of the work.

In witness whereof, I hereunto subscribe my name, as attested by the two subscribing witnesses.

RICHARD E. ROSEWARNE.
